Charles T. Parisi, Pawtucket, R. I., assignor to Parisi Tool Company, Providence, R. I., a corporation of Rhode Island

Application December 16, 1950, Serial No. 13,456

Term of patent 14 years

(Cl. D45—144)

To all whom it may concern:

Be it known that I, Charles T. Parisi, a citizen of the United States, residing in Pawtucket, State of Rhode Island, have invented a new, original, and ornamental Design for a Bracelet or Similar Article, of which the following is a specification, reference being had to the accompanying drawing, forming a part hereof.

Figure 2 is an edge elevational view of the bracelet or similar article with the clasp elements and a portion of the center omitted for convenience of illustration only.

I claim:

The ornamental design for a bracelet or similar article, as shown and described.

CHARLES T. PARISI.
